Primary Examiner — Amber R Stiles*Assistant Examiner* — Tia Ruth-Renee Polidori(74) *Attorney, Agent, or Firm* — Apex Juris, PLLC; R. Lynette Wylie(57) **CLAIM**

The ornamental design for an embedded oven, as shown and described.

DESCRIPTION

FIG. 1 is a perspective view of an embedded oven;

FIG. 2 is a perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

The broken lines are included for the purpose of illustrating the portions of the embedded oven that form no part of the claimed design.

1 Claim, 8 Drawing Sheets(56)
